COMBINED BOTTLE OPENER AND SCREWDRIVER

Harvey N. Bliss, Windsor, Conn., assignor to The Britton Corporation, Newington, Conn., a corporation of Connecticut

Filed Dec. 15, 1966, Ser. No. 5,057

Term of patent 14 years

(Cl. D44—29)

FIG. 1

FIG. 2

FIG. 4

FIG. 3

FIGURE 1 is a perspective view of a combined bottle opener and screwdriver showing my new design with the blade in the open position;

FIGURE 2 is a side elevational view with the blade in closed position;

FIGURE 3 is a similar view with the blade in open position; and

FIGURE 4 is a left and elevational view thereof.

The essential feature of my design resides in the taper of the case and the blade towards the pivot in combination with the arrangement of the cap removing hook member adjacent the free end of the blade.

I claim:

The ornamental design for a combined bottle opener and screwdriver, as shown and described.
